Primary Examiner — Leanne Was-Englehart(74) *Attorney, Agent, or Firm* — Silicon Valley Patent Group LLP; Thomas C. Chan(57) **CLAIM**

The ornamental design for a tool, as described and shown.

DESCRIPTION

FIG. 1 is a perspective view of a tool according to the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side plan view thereof; and,

FIG. 7 is a right side plan view thereof.

The broken lines shown in FIGS. 1-7 are environmental only and form no part of the claimed design.

1 Claim, 5 Drawing Sheets(56)
